UNITED STATES PATENT OFFICE.

JOHN E. TRIMBLE, OF ALBANY, INDIANA.

MACHINE FOR SKINNING TOMATOES.

SPECIFICATION forming part of Letters Patent No. 759,773, dated May 10, 1904.

Application filed January 8, 1903. Serial No. 138,811. (No model.)

To all whom it may concern:

Be it known that I, JOHN E. TRIMBLE, a citizen of the United States, and a resident of Albany, in the county of Delaware and State of Indiana, have made certain new and useful Improvements in Machines for Skinning Tomatoes, of which the following is a specification.

My invention is an improvement in apparatus for use in removing the skins from tomatoes, and has for an object to provide means whereby suction may operate in connection with the perforated bed to draw the skins from the tomatoes and to permit the pulp to discharge with the skin removed; and the invention consists in certain novel constructions and combinations of parts, as will be hereinafter described and claimed.

In the drawings, Figure 1 is a perspective view of an apparatus embodying my invention. Fig. 2 is a vertical longitudinal section of the suction-chamber. Fig. 3 is a cross-section on about line 3 3 of Fig. 1, parts being omitted; and Fig. 4 is a detail cross-section on about line 4 4 of Fig. 3.

In carrying out my invention I provide a suction-chamber A, which is represented as rectangular in form, somewhat elongated, and mounted pivotally at A' between its ends, so it may be adjusted to any desired inclination, means being provided for such purpose and consisting, as shown, of a screw B, threaded at B' in a suitable bearing, swiveled at B² to the chamber A, near one end thereof, and having a hand-wheel B³, by which it may be readily turned to quickly adjust the suction-chamber to any desired inclination. In constructing the chamber A, I may prefer to employ a framing consisting of angle-iron or steel strips C and a covering of sheet metal or other substance for the ends, sides, and bottom of the chamber, the top of the chamber being formed of a perforated slab or slabs D, of marble or other suitable material, perforated at intervals with holes of such size as to permit the skin of the tomatoes to be drawn through by the suction and the pulp to discharge at the end E, where a suitable chute may be provided, as shown.

As shown and preferred, the slab D is made in two sections lapping together at d, and the

sections are perforated with holes d', arranged in comparatively close relation, as will be understood from Figs. 1, 2, and 3.

Guard-strips F extend along the opposite sides and project above the slab D and are provided with slots F', in which operate the controlling-bars G, the latter being pivoted at G' to the guards F and having the outer or handle portions G² and the inner or turning portions G³, the latter projecting in use over the slab D and operating to cause the tomatoes to turn or roll as they descend the slab, so that every portion of the skin will be exposed to the direct action of the suction. The angle of the turning portions G³ may be varied at will by the operator by turning bars G on the pivot G', the latter being made sufficiently tight to hold the bars G in any position to which they may be set by the operator. The upper edges of the turning portions of the bars G are roughened or corrugated at g, (see Fig. 1,) and a rubber or other flexible strip g' projects from the under side of the controlling-bar and bears against the upper surface of the slab D and operates to scrape all portions of the tomatoes loose from the slab and also aids the tight pivots G' in holding the controlling-bars in any position to which they may be adjusted by the operator.

In operation the tomatoes after having been suitably scalded, which may be accomplished by any suitable mechanism, are discharged by a carrier H onto the upper end of the slab D, a scraper H' projecting upwardly from the slab D to remove the tomatoes from the conveyer H, as is best shown in Fig. 1, and as the tomatoes pass down the slab D by gravity, the inclination of the said slab being controlled in the manner before described, the tomatoes will pass over the perforations d' and will be exposed to the action of the suction within the box or chamber A, and the tomatoes will be turned and caused to move from side to side by means of the controlling-bars, so the suction will be caused to operate upon all portions of the tomatoes and thoroughly remove the skins therefrom.

Suction is produced within the chamber or box A by a suction-fan in the manner presently described, and I also provide means for

discharging air above the slab D, consisting, preferably, of a pipe I, leading from any suitable form of compressor or fan and discharging to a main pipe I', which extends 5 longitudinally over the center of the slab D and has lateral branch or discharge pipes I² at intervals perforated to direct the blast of air downwardly on the tomatoes on the slab D, so the blast of air above the slab will co- 10 operate with the suction produced below the slab in forcing the skins off the tomatoes and through the perforations D' into the box or chamber, as desired.

Suction is produced within the box or chamber A by any suitable means, that shown consisting of a fan J, operating within a tube K, which connects at K' with the box or chamber A at one side of the latter, the connections between the tube K and box A being controlled 15 by the screen L, whose frame M is 20 slideable in suitable guides, as will be understood from Fig. 4, into and out of position across the connection between the tube K and the box A, so the said screen can be inserted 25 and removed whenever desired.

The fan J may be driven by any suitable motor device or power and is shown with its shaft J' provided with a pulley J², receiving the belt J³, the said pulley J² and the 30 belt J³ being incased within the tube K in a suitable housing N, so the liquor drawn from the tomatoes cannot reach the pulley and cause the belt to slip.

In order to control in a measure the force 35 of the suction exerted within the box or chamber A, I provide said box with openings in one side, preferably two in number, and arrange damper-plates O to close said openings, the dampers O being pivoted at O' at 40 one edge and connected at their opposite edges by a link P, having a handle P', so it can be operated to open the dampers to any desired degree or to close the same, as may be desired.

45 At its lower end the box A is provided with a valved outlet at Q for any liquor that may get into said box, and a manhole may be provided in the same end of the box and covered by a removable plate R when in use, as will 50 be understood from Fig. 2 of the drawings.

Manifestly I do not desire to be limited in the broad features of my invention to the special construction of the suction box or chamber or the devices co-operating therewith, as 55 shown and described, as these may be varied without departing from some of the broad features of my invention. It will also be understood that my invention will be found useful in removing skins from peaches and other 60 fruit and vegetables and is not limited to use in removing the skins of tomatoes.

It will be understood that in preparing the tomatoes for treatment by my invention they may be scalded in any suitable manner and

will be delivered to the upper end of the bed 65 in a blistered condition with the skin loosened on the larger portion of the tomato. It will also be understood that ordinarily the tomatoes will be delivered to the upper end of the slab or bed while still hot; but I do not desire to 70 be limited in the broad features of my invention to this, as in treating some fruits and vegetables it may not be necessary to scald or heat the fruit, and my improvement relates to the means for removing the skin as before described and as pointed out in the appended 75 claims.

Having thus described my invention, what I claim as new, and desire to secure by Letters Patent, is—

1. The machine herein described for removing skins from scalded tomatoes consisting of the suction box or chamber having a perforated slab at its upper side and provided at the opposite sides of said slab with upwardly-projecting guards having longitudinal slots, the controlling-bars pivoted within said slots to the guards and having their upwardly-facing edges corrugated and provided with flexible strips on their under sides, the air-blast devices operating above the said slabs, the suction devices connected with the box or chamber to produce a suction through the perforations of the slab, the damper devices connected with the box or chamber, a support to 95 which the box or chamber is pivoted, and means for adjusting the box or chamber on its pivot substantially as set forth.

2. A machine for removing skin from tomatoes and the like substantially as described 100 comprising a slab or plate to which the tomatoes may be supplied, such plate being provided with perforations spaced apart whereby slab-surfaces for supporting the pulp are provided between the adjacent perforations, and means for producing suction down through the perforations in the said slab or plate whereby to draw the skins of the tomatoes through the said perforations substantially as set forth.

3. The combination in a machine for removing skin from tomatoes and the like of the inclined perforated slab or plate, means for producing suction through the perforations of said plate, and controlling-bars operating 115 above the plate and adjustable to different positions thereon substantially as set forth.

4. The combination in a machine for removing skin from tomatoes and the like with the inclined perforated slab or plate and the suction devices of the controlling-bars operating 120 above the slab or plate substantially as set forth.

5. The combination in a machine for removing skin from tomatoes and the like of the 125 inclined perforated slab or plate, means for producing suction through the perforations of said plate, the upwardly-projecting guards at

the opposite sides of the slab or plate, and the controlling-bars pivoted to said guards substantially as set forth.

6. The combination in a machine for removing skin from tomatoes and the like of the perforated slab or plate, means for producing suction below said plate and the air-blast devices discharging above said plate substantially as described.

10. 7. In a machine for skinning tomatoes the suction box or chamber having a perforated top and means for producing suction down through said box, combined with supports to which said box is pivoted and means for adjusting the box to different inclinations on said pivot substantially as set forth.

8. The combination in a machine for removing skin from tomatoes and the like with the suction box or chamber having a perforated 20 slab or plate at its top and damper-openings, of damper-plates controlling said openings, and connections between said plates whereby they may be operated simultaneously and means for producing suction below the perforated plate substantially as set forth.

9. The combination in a machine for removing skin from tomatoes and the like with the suction box or chamber having the perforated slab or top plate, of the controlling-bars arranged at intervals along the said slab from its upper to its lower end and adjustable to different angles relative thereto substantially as set forth.

10. In a machine for skinning tomatoes a 35 suction box or chamber having a frame of angle metal, sheet-metal side, end and bottom plates covering said frame, and a perforated slab or top plate and means for producing suction in said box substantially as set forth.

40. 11. The combination in a machine for skinning tomatoes and the like of the box or chamber having the slab or plate provided with perforations spaced apart whereby to provide slab-surfaces between the adjacent 45 perforations to support the pulp, and the suction devices whereby to produce a suction within said box or chamber substantially as set forth.

12. The combination in a machine for removing skin from tomatoes and the like with the perforated slab of the controlling-bars operating above said slab and having their edges facing the upper end of the slab roughened whereby to effect a turning of the tomatoes 55 substantially as set forth.

13. A machine for use in removing skin

from scalded tomatoes or the like which comprises a perforated bed and pneumatic devices whereby suction may operate in connection with the perforated bed to draw the skin 60 from the tomatoes substantially as set forth.

14. A machine for use in removing skin from scalded tomatoes which comprises a bed arranged at an incline whereby the tomatoes may travel down the same by gravity said bed 65 being provided with perforations spaced apart providing surfaces between the perforations to support the pulp and pneumatic devices whereby to draw the skins from the tomatoes as they pass over the bed substantially as described. 70

15. As an improved means for removing skin from scalded tomatoes, a perforated bed, pneumatic devices operating in connection with said perforated bed to draw the skins 75 from the tomatoes and devices for shifting the tomatoes laterally upon the bed as they pass thereover substantially as described.

16. A machine for removing skins from tomatoes and the like, consisting of a slab of 80 marble, having perforations and supported at an incline whereby the tomatoes may be moved down upon said slab over such perforations, and means for producing suction down through the perforations in the slab whereby 85 to draw the skins from the tomatoes and through said perforations in the slab, substantially as set forth.

17. A machine for removing skins from scalded tomatoes and the like, comprising a 90 suction-chamber having a slab covering its top, and provided with perforations, said slab being supported at an incline, and means for producing suction in the chamber whereby to draw the skins of the tomatoes through the 95 perforations in the top slab, substantially as set forth.

18. A machine for removing skins from tomatoes and the like, comprising the suction-chamber having its top in the form of a slab 100 provided with perforations, means for producing suction in the chamber, whereby to draw the skins from the tomatoes and through the perforations in the top slab, and a main and branch discharge-pipes extending over 105 the slab and adapted to direct a blast of air downwardly toward the slab, substantially as set forth.
